UNITED STATES PATENT OFFICE.

EDMUND RUMPLER, OF GOGGINGEN, NEAR AUGSBURG, AND ALBERT RENNAU, OF AUGSBURG, GERMANY; SAID RENNAU ASSIGNOR TO SAID RUMPLER.

REFRIGERATING APPARATUS.

Application filed April 25, 1921. Serial No. 464,488.

To all whom it may concern:

Be it known that we, EDMUND RUMPLER, of Goggingen, near Augsburg, and ALBERT RENNAU, of Augsburg, Germany, citizens 5 of the Republic of Germany, have invented certain new and useful Improvements in Refrigerating Apparatus, of which the following is a specification.

This invention relates to a novel absorption refrigerating apparatus specially designed for cooling a refrigerator, although it may also be used for cooling rooms, and is principally designed to produce an apparatus of this kind, which will properly and 15 safely operate without attendance.

In the accompanying drawing we have represented an example of carrying our invention into effect. The boiler *k*, which serves as gas-producer of the apparatus, contains the electric heating cartridge *p* and a small steel tube *a*, which is preferably pivoted at *f*, as shown in the drawing, in order to be able to swing in a vertical plane, in such a manner that it will either be positioned in the dotted or in the position shown 20 in full lines. The latter position will be effected through the action of the electromagnet *m* or the like, which is inserted into the electric circuit *w* serving for heating the boiler *k*. The ammonia-gas, which is liberated by heating the boiler *k*, will now flow unobstructed in the direction of the upper arrow through the conducting pipe *l* and will thus be carried into the condenser *c*, 25 where it will condense to a liquid by reason of the effect of the cooling-water so that it will trickle through the container *s* into the evaporator *v*.

When the gas has been driven off, the electric circuit is interrupted in any suitable 40 way. For automatically opening the circuit, recourse may be had to a heat-responsive element such as a thermometer *t* controlling an electric circuit *r* which in turn may be utilized in well-known manner for controlling the electric circuit *w* including the cartridge *p* and the electromagnet *m*. When 45 the circuit *w* is open then the steel tube *a* will swing downwardly and assume the position indicated in dotted line. As the boiler liquid cools off, a partial vacuum will be formed causing the re-absorption of the ammonia from the evaporator *v*. The process 50 of cooling of the boiler liquid can be has-

tened or promoted in any suitable manner as 55 is well understood in the art.

The principal point of novelty of our invention is the arrangement including the tube *a* which, in the full line position, carries off the gas given off from the liquid 60 and in the dotted line position permits the gas during the process of evaporation in the evaporator to return to and be reabsorbed by the liquid in the boiler.

When the condensed or liquefied gas has 65 been fully evaporated and re-absorbed by the boiler liquid, the circuit *w* is again energized. The tube *a* is again lifted out of the liquid by the action of the magnet *m* and the cycle is repeated. 70

By inserting a properly constructed and economically cooled condenser *c* between the boiler *k* and the evaporator *v* it will further be possible to utilize this small apparatus for cooling rooms. The liquefied gas has a 75 comparatively low temperature and the period of distillation is comparatively short so that no appreciable heat transfer will take place from the liquid in the accumulator or storage reservoir and the evaporator 80 to the air in the room to be cooled. Moreover the air which may be warmed up remains at the top of the refrigerator where it can have little effect.

Furthermore, the capacity of the evaporator can be so dimensioned that the period 85 of heating, which takes a comparatively short time, will be followed by a period of evaporation lasting several hours, and during this latter period the cooling will be 90 effected by air which is a poor conductor of heat. A closure *j* which may be of the type of a so-called Venetian blind will close up the evaporator from the room *r*.

The accumulator *s* may also be so constructed 95 that a container *e* may be placed into the same for ice-cream making.

While we have specifically referred to electrical means for heating the boiler liquid, it is understood that other heating 100 means are applicable.

In the foregoing we have shown and described the tube *a* as movable relatively to the boiler *k* and this arrangement constitutes the preferred embodiment of the invention. 105

However, in the broader aspect of the invention, the tube *a* may be stationary rela-

tively to the boiler and the boiler together with the tube *a* may be angularly turned to at one time cause the tube *a* to dip into the boiler liquid and at another time to open 5 into the vapor space of the boiler.

Having thus described our invention we claim as new and desire to secure by Letters Patent of the United States of America:

1. In a refrigerating apparatus including 10 a stationary evaporator, a closed vessel containing a liquid adapted to absorb a gas, a gas tube for delivering gas therefrom or thereto and having an opening disposed within the vessel, and means for changing 15 the relative position of the liquid level and the opening of the tube to either immerse the opening of the tube in the liquid or to dispose it above the level of the liquid.

2. In a refrigerating apparatus, a closed 20 vessel containing a liquid adapted to absorb a gas, a tube disposed in the vessel and extending to the outside, the tube being movable relatively to the vessel and having a portion presenting an opening, and means 25 for moving the tube portion to a position in which its free end is immersed in the liquid or to a position in which it is disposed above the level of the liquid.

3. A refrigerating apparatus comprising 30 a vessel containing a liquid and adapted to alternately operate as a boiler and as an absorber, a stationary evaporator, a fluid connection between the vessel and the evaporator, said connection including a tube disposed in the vessel, and means for changing 35 the relative position of the liquid and the tube to either immerse the free end of the tube in the liquid or to dispose it above the level of the liquid.

40 4. A refrigerating apparatus comprising a vessel containing a liquid and adapted to alternately operate as a boiler and as an absorber, an evaporator, a fluid connection between the vessel and the evaporator, said connection including a tube disposed in the vessel and angularly movable relative thereto, and means for moving the tube to a position in which its free end is immersed in the liquid or to a position in which it is disposed 45 above the level of the liquid.

50 5. A refrigerating apparatus comprising a vessel containing a liquid and adapted to alternately operate as a boiler and as an absorber, a stationary evaporator, a fluid connection between the vessel and the evaporator, said connection including a tube disposed in the vessel, means for changing the relative position of the liquid and the tube to either immerse the free end of the tube in 55 the liquid or to dispose it above the level of the liquid, and means for applying heat to the liquid during the period the tube is 60

above the level of the liquid and shutting off the supply of heat when the tube is immersed.

6. Refrigerating apparatus of the absorption type, including a vessel adapted to be partly filled with liquid and serve alternately as an absorber and as a boiler, a gas conduit for delivering gas therefrom or thereto, 70 electric means for heating said vessel, and electric means for operatively connecting the vapor space or the body of liquid in said vessel with said conduit, both of said electric means being arranged in the same circuit for simultaneous operation, whereby said conduit communicates with the vapor space during heating operation, and with the body of liquid during intervening periods.

7. Refrigerating apparatus of the absorption type, including a vessel adapted to be partly filled with liquid and serve alternately as an absorber and as a boiler, a gas conduit for delivering gas therefrom or thereto, 85 and an oscillating member disposed entirely within said vessel for operatively connecting said conduit with the vapor space in said vessel during use of the vessel as a boiler and connecting it with the liquid space in 90 said vessel during use of said vessel as an absorber and electric means for operating said oscillating member.

8. Refrigerating apparatus of the absorption type, including a vessel adapted to be 95 partly filled with liquid and serve alternately as an absorber and as a boiler, a gas conduit for delivering gas therefrom or thereto, and electric means for applying heat to the vessel, said conduit being automatically connected with the liquid space of the vessel upon the shutting off of the supply of heat.

9. A refrigerating apparatus comprising 100 a vessel containing a liquid and adapted to alternately operate as a boiler and as an absorber, an evaporator, a fluid connection between the vessel and the evaporator, said connection including a tube disposed in the vessel, electric means for changing the relative position of the liquid and the tube to either immerse the free end of the tube in the liquid or to dispose it above the level of the liquid, and electric means for applying heat to the liquid during the period the tube is above the level.

In testimony whereof we have affixed our signatures in presence of two subscribing witnesses.
